(57) CLAIM

The ornamental design for an angled bowl, as shown and described.

DESCRIPTION

FIG. 1 is a perspective view of the angled bowl of my design;

FIG. 2 is a left side elevational view of the angled bowl of my design, the right side elevational view being a mirror image thereof;

FIG. 3 is a top plan view of my angled bowl;

FIG. 4 is a front elevational view of my angled bowl;

FIG. 5 is a rear elevational view of my angled bowl; and, FIG. 6 is a cross-sectional view of my angled bowl taken along line 6—6 of FIG. 3.
